UNITED STATES PATENT OFFICE.

JOHN REGAN, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

WARP STOP MOTION FOR LOOMS.

Application filed June 21, 1927. Serial No. 200,463.

This invention relates to improvements of warp stop motions and it is the general object of the invention to provide a motion which will operate satisfactorily with a warp 5 having threads of different kinds or sizes and degrees of fineness.

In the weaving of certain fabrics such as fancy worsteds it is not uncommon to employ distinctively colored decorative warp 10 threads of silk to form stripes in the fabric. These decorative threads are very fine and are ordinarily unable to support the kind of drop wires which are used for the relatively stronger and coarser worsted yarns and I 15 have found that attempts to mix two weights of drop wires in the same bank or group does not give satisfactory results. The reason for this is that the space between the separator bars against which the drop wires 20 are moved at the time of indication of warp fault is made relatively wide for the heavier drop wires and this space is found to be so wide that the lighter and narrower drop wires have sufficient lost motion before engaging 25 one of the separator bars to prevent operation of the motion. It is an important object of my present invention to group all of the finer and lighter drop wires in one bank and provide separator bars for this 30 bank which are closer together than are the separator bars of the main part of the warp stop motion.

When a knock-off motion of the type set forth in patent to Holmes No. 1,360,638 is 35 employed the tension on the yielding spring is set to operate satisfactorily with the heavier drop wires but I find that a pressure satisfactory for the drop wires on the worsted yarns is too great for the lighter drop wires 40 for silk yards and this is an additional reason why the separator bars for the drop wires on the silk yards should be close enough to require the lighter drop wires to stop the loom when a silk thread 45 breaks. If the relatively heavier pressure necessary for the larger drop wires were applied to the lighter drop wires and the latter were free to move in a relatively large space before engaging the separator bars the motion 50 would operate unsatisfactorily when a fault occurred in the silk threads.

When fine silk threads and relatively coarse worsted yarns are wound on the same beam the silk yarn, being of smaller diameter, will wind more closely so that a given

length will occupy less space than is the case with the larger worsted yarns. The result of this is that in the letting-off of the beam there is an unevenness in the tension of the silk and worsted threads. It is a further object of my present invention to provide a motion wherein all of the finer or silk threads may be subjected to a drop wire pressure different from that exerted on the coarser threads, the purpose being to tend 60 to correct any unevenness of tension which might result in the letting-off of the silk threads.

With these and other objects in view which will appear as the description proceeds, my invention resides in the combination and arrangement of parts hereinafter described and set forth in the claims.

In the accompanying drawings, wherein I have shown a convenient embodiment of 75 my invention,

Fig. 1 is a side elevation of a portion of a warp stop motion having my invention applied thereto,

Fig. 2 is a vertical section taken through 80 the warp stop motion looking from the rear of the motion as shown in Fig. 1, and

Fig. 3 is a diagrammatic top plan of a portion of the motion showing the relation between the coarse and fine warp threads 85 and the different types of drop wires supported thereby.

Referring to Figs. 1 and 2 I have shown the operating or head end of a warp stop motion having a frame 10 with an upstanding arm 11 in which is secured a stud 12. An actuating lever 13 is pivoted on said stud and is given a periodic oscillation by means of an upright connector 14 operated by any approved mechanism not shown such as a 90 cam on the bottom shaft of the loom. Said lever is provided with a knock-off hook 15 and is further provided with an arm 16 in which is journaled gudgeon 17 of a swivel bearing 18. Freely extending therethrough 100 is a rod 19 the lower end of which is U-shaped and extends upwardly to have connection at 20 with a small bell crank lever 21. A light compression spring 22 is interposed between the swivel bearing 18 and a 105 collar 23 adjustably secured to the rod 19.

The bell crank lever 21 has a downwardly depending arm 24 which has connection with one end of a horizontally extending link 25. Said link has pivotal connection 110

with a plurality of depending arms 26 and also with an indicator link 27. A clip 28 is adjustably secured to the link 27 by screw 29 and carries a pin 30 lying under the tail 31 of a dog 32 which is adapted for cooperation with the hook 15. Dog 32 is pivotally supported on a knock-off lever 33 pivoted on the stud 12 and connected by a knock-off rod 34 to stopping mechanism not shown. The 10 links and bell crank lever 21 are connected with non-circular oscillating detector rods to be described hereinafter.

In operation lever 13 oscillates back and forth about stud 12 and arm 16 will bear 15 downwardly on compression spring 22 to lower the rod 19, said rod being loose with respect to the arm 16. So long as downward movement of the rod is uninterrupted the link 25 will move to the left from the 20 position shown in Fig. 1 and indicator link 27 will be rocked to raise pin 30 so that the right hand end of dog 32 will be depressed as the hook 15 moves to the left. Said hook will therefore have an idle movement and 25 the knock-off lever 33 would remain at rest to permit continued running of the loom. At the time of a warp fault, however, the link 25 will be held against movement to the left and the pin 30, remaining in low position, will leave dog 32 in the path of hook 15 and as the latter moves to the left the knock-off lever 33 and rod 34 will be given 30 a loom stopping movement. The matter thus far described is of common construction and may be as set forth in the aforementioned patent to Holmes but forms no part of 35 my present invention.

My present invention relates to the arrangement of the drop wires so that the 40 heavy wires which correspond to the relatively coarse yarn may be grouped together and the lighter drop wires which correspond to the finer decorative threads may also be grouped together apart from the heavier 45 drop wires. In the particular form of invention shown herein the bell crank lever 21 and the links 26 have driving connections with oscillating detector rods 40 while the indicator link 27 has a driving connection 50 with another oscillating detector rod 41. Said detector rods may be of substantially the same cross section or if desired the rod 41 may be made slightly smaller than the rods 40.

55. The drop wires for the relatively coarse threads W are shown at 42 and are heavier and wider than drop wires 43 used on the silk warps S. All of the drop wires are provided with slots 44 the upper ends of 60 which are restricted as at 45, said restricted ends of the slots cooperating with non-circular detector rods to prevent angular movement of the latter at the time of warp fault as set forth in my prior Patent No. 1,265,112, 65 reissued March 30, 1920, No. 14,829.

It is customary in warp stop motions of the type set forth herein to employ so-called separator bars extending under the warp threads and serving to separate the drop wires into banks. As shown herein I have 70 provided several separator bars, the one to the left indicated at 46 being relatively high and the three bars to the right thereof being indicated at 47 and being relatively lower. Another high separator bar 48 may be located to the right of the last low bar 47. These separator bars may be spaced horizontally to define between them equal spaces in which the lower ends of the larger drop wires 42 may extend. The separator bars 80 cooperate with the drop wires and the oscillating detector rods to prevent movement of the latter when a drop wire is in fallen position. Another relatively high separator bar 49 is employed at the right hand side of 85 the motion as viewed in Fig. 2 and defines with separator bar 48 a relatively narrow space for the lower ends of the lighter and narrower drop wires 43.

In Fig. 3 I have indicated diagrammatically the relation of the separator bars, warp threads and drop wires and in said figure I have represented the relatively coarse warp threads W and the finer warp threads at S as extending horizontally. 95 Each of the coarse threads will have a drop wire 42 thereon while each of the fine warp threads has one of the smaller drop wires 43. As shown clearly in Fig. 3 the lighter drop wires are grouped in one bank located 100 between the separator bars 48 and 49, while the heavier drop wires are located in parallel banks and extend in the wider spaces between the remaining separator bars. It will be noticed by referring to Fig. 2 that 105 the clearance between the edges of the small drop wires 43 and the adjacent separator bars is substantially the same as the clearance between the edges of the heavier drop wires 42 and the separator bars lying 110 adjacent thereto. I find that as a matter of practical construction the oscillating rod 41 should be a little nearer the adjacent oscillating rod 40 than the distance between adjacent rods 40. The separator bars may 115 be supported by a bracket 50 held to the frame 10 and shown in detail in Patent No. 1,496,361.

By the construction set forth herein I am able to segregate the lighter drop wires 120 which rest on the finer yarns and provide a relatively smaller space between separator bars for said lighter drop wires so that they will be as effective in operating the warp stop motion as are the larger drop 125 wires. As previously stated I found that when the smaller drop wires made necessary by the finer warp threads were placed in the same banks with the heavier drop wires there was so much space between the 130

edges of the small drop wires and the separator bars that said lighter detector did not operate to stop the loom satisfactorily. This defect could not be corrected by applying heavier drop wires to the silk threads as the latter do not operate satisfactorily with the heavy drop wire and furthermore the defect could not be corrected by applying light drop wires to the heavier threads because of the fact that a break in a coarse thread some distance from the warp stop motion would leave a free end so heavy that a light drop wire would remain supported and would therefore not fall into stopping relation with its oscillating rod. I find it necessary not only to employ two different weights and widths of drop wires but also find it highly desirable to group these drop wires so that the light and narrow ones shall be in one bank and the heavier drop wires in the other bank. I find that the finer threads S operate better when the separator bar 48 is of the same height as the bar 49, these high bars supporting the finer yarns so as to prevent the drop wires 43 from falling into stopping position with respect to the detector rod 41.

From the foregoing it will be seen that I have provided a warp stop motion wherein the relatively heavy drop wires are separated from the finer and lighter wires and wherein the spring 22 can be set to operate with equally satisfactory results whether the heavy or the light drop wires are in stopping position with respect to their oscillating detector rods. It will further be seen that the separator bars against which the lower ends of the drop wires are moved at the time of a warp fault are given proper spacings so that the idle motion of the drop wires before they engage the separator rods will be substantially the same irrespective of the type of drop wire which may be indicating. Furthermore, the separator bars 48 and 49 serve to hold the drop wires 43 in proper position relatively to the detector rod 41.

Having thus described my invention it will be apparent that changes and modifications may be made therein by those skilled in the art without departing from the spirit and scope of the invention and I do not wish to be limited to the details herein disclosed, but what I claim is:

1. In a warp stop motion for looms having relatively coarse and relatively fine warp threads, relatively wide heavy drop wires for the coarse warp threads, relatively narrow light drop wires for the finer warp threads, means to separate the lighter from the heavier drop wires, and a plurality of separator bars to separate said drop wires into banks, the clearance between the edges of the narrower drop wires and the adjacent separator bars being substantially the same

as the clearance between the edges of the wider drop wires and the separator bars adjacent thereto.

2. In a warp stop motion for looms having relatively coarse and relatively fine warp threads, relatively light and narrow drop wires for the finer yarns arranged in one group, relatively heavier and wider drop wires for the heavier warp threads arranged in another group, an oscillating detector rod for each group, separator bars to hold the groups apart in spaced relation and to cooperate with an oscillating detector rod and a fallen drop wire to arrest movement of the oscillating detector rod, so the separator bars adjacent the group of lighter drop wires being nearer together than the separator bars lying adjacent the heavier group of drop wires.

3. In a warp stop motion for looms having relatively coarse and relatively fine warp threads, a group of light relatively narrow drop wires for the finer yarns, another group of heavier relatively wide drop wires for the coarse warp threads, an oscillating detector rod for each group of threads, a resilient driving means to oscillate said detector rods, and separator bars to cooperate with the detecting rods, said separator bars defining a relatively narrow space for the group of narrower drop wires and defining another relatively wider space for the group of wider drop wires, said separator bars and oscillating detector rods cooperating with a fallen drop wire to arrest oscillation of the corresponding detector rod.

4. In a warp stop motion for looms having relatively coarse and relatively fine warp threads, a plurality of separator bars defining substantially parallel spaces and certain of said bars being farther apart than other of said bars to define spaces of varying widths, a group of relatively wide drop wires for the coarse warp threads located in a relatively wide space, another group of relatively narrow drop wires located in a relatively narrow space, and oscillating means cooperating with each bank of drop wires and the separator bars to stop the loom when any of the drop wires fall into engagement with the corresponding rod.

5. In a warp stop motion for looms having coarse and fine yarn, a set of relatively heavy wide drop wires for the coarser yarns arranged in a group, a set of lighter narrow drop wires for the fine yarns arranged in another group, an oscillating detector rod for each group to be engaged by a fallen drop wire, yielding driving means to oscillate the detector rods, fixed stops against which the drop wires may move, said driving means yielding when a drop wire is in fallen position in engagement with the corresponding oscillating detector rod but said driving means moving the drop wire against

the fixed means, the amount of movement given any of the drop wires to bring the same into engagement with fixed stopping means being substantially the same.

- 5 6. In a warp stop motion for a loom having relatively coarse and fine yarns, a set of relatively heavy drop wires arranged in a plurality of groups, one relatively heavy drop wire being for each coarse thread, a 10 set of light drop wires for the fine threads being arranged in a group separate from the drop wires of the coarse threads, a pair of relatively high separator bars defining a 15 space for the light drop wires, a set of separator bars certain of which are high and certain of which are low to define spaces for the drop wires of the coarse yarns, and means to stop the loom when any of the drop wires fall.

- 20 7. In a warp stop motion for a loom having relatively coarse and fine yarns, a plurality of sets of relatively heavy drop wires arranged in a plurality of groups, one relatively heavy drop wire being for each coarse 25 thread, a set of light drop wires for the fine threads arranged in a group separate from the drop wires of the coarse threads, a pair of relatively high separator bars defining a space for the light drop wires, a set of separator bars certain of which are high and certain of which are low to define spaces for the drop wires of the coarse yarns, the separator bars being so disposed that the lighter drop wires are at one side of the 30 motion and the coarser drop wires at the other side, and means to stop the loom when any of the drop wires fall.

- 35 8. In a warp stop motion for looms having relatively coarse and relatively fine warp 40 threads, a group of relatively wide drop wires for the coarse warp threads, a separate group of relatively narrow lighter drop wires for the finer warp threads, means to separate the narrower drop wires from the 45 wider drop wires, all the drop wires having

slots therein with a restricted upper portion, a non-circular oscillating detector rod passing through the slots and engageable by the restricted portion of the slot of a fallen drop wire, said rod moving a fallen drop wire 50 against the means to cause deflection of a fallen drop wire when moved against the means, and means to stop the loom when any of the drop wires fall.

55 9. In a warp stop motion for a loom having relatively coarse and fine yarns, a set of relatively heavy and inflexible drop wires arranged in a group for the coarse yarns, another set of relatively light and flexible drop wires arranged in another group for 60 the fine yarns, separator bars for the heavy drop wires certain of which are relatively high and others of which are relatively low, high separator bars defining a space occupied by the light and relatively flexible drop 65 wires, and a plurality of aligned oscillating elements one for each set of drop wires to cooperate with fallen drop wires tending to move a fallen drop wire toward a separator bar.

70 10. In a warp stop motion for looms having relatively coarse and relatively fine warp threads, a group of relatively wide drop wires for the coarse warp threads, a separate group of relatively lighter drop wires for 75 the finer warp threads, means to separate the lighter drop wires from the wider drop wires, all the drop wires having slots therein with a restricted upper portion, a non-circular oscillating detector rod passing through 80 the slots and engageable by the restricted portion of the slot of a fallen drop wire, said rod moving a fallen drop wire against the means to cause deflection of a fallen drop wire when moved against the means, and 85 means to stop the loom when any of the drop wires fall.

In testimony whereof I have hereunto affixed my signature.

JOHN REGAN.
